UNITED STATES PATENT OFFICE.

DAVID W. LYNCH, OF LANCASTER, PENNSYLVANIA.

DESIGN FOR A BABY TRAY.

Application filed March 31, 1925. Serial No. 12,968. Term of patent 7 years.

To all whom it may concern:

Be it known that I, DAVID W. LYNCH, a citizen of the United States, residing at Lancaster, in the county of Lancaster and State of Pennsylvania, have invented a new, original, and ornamental Design for a Baby Tray, of which the following is a specification, reference being had to the accompanying drawing, forming part thereof.

The figure is a perspective view of a baby tray showing my new design.

I claim:

The ornamental design for a baby tray as shown.

DAVID W. LYNCH.
